WARREN E. COOPER, OF NEW YORK, N. Y., AND FREDERICK K. HABENICHT, OF ST. LOUIS, MISSOURI, ASSIGNEES TO WESTERN RAILWAY EQUIPMENT COMPANY, OF ST. LOUIS, MISSOURI, A CORPORATION OF MISSOURI

PLACARD HOLDER FOR TANK CARS

Application filed July 19, 1928. Serial No. 293,999.

It is the practice to apply to tank cars used in transporting inflammable liquids, acids or other material of a dangerous nature, a placard indicating not only the contents of the 5 car but also its condition—whether full or empty. These placards have usually been tacked or pasted to a support carried by the running-board, or two placards have been carried on opposite sides of a reversible 10 holder.

It is the object of the present invention to provide a simple and effective holder which will accommodate one or metallic placards and is also adaptable to the usual paper placards.

In the accompanying drawings which illustrate one form of holder made in accordance with our invention, Figure 1 is a front elevation; Figure 2 is an enlarged section of 20 the line 2—2 of Figure 1; Figure 3 is an enlarged section taken on the line 3—3 of Figure 1; Figure 4 is a top plan view of one end of the holder; and Figure 5 is a reduced view showing a modified form of support for the 25 holder.

Referring first to Figure 1, carried by the running-board 1 of the car is an upright 2 to which the holder 3 is secured by bolts 4. The holder is formed of a substantially square 30 piece of sheet metal having formed in it, along one of its diagonals, a pair of cup-shaped depressions 5 in which are holes 6 for the passage of the bolts. Being of considerable size these depressions add to the rigidity 35 of the holder while forming pockets for the heads of the bolts and also spacing the holder from the support. Owing to the diagonal arrangement of the pockets the holder may be secured either to an upright, as shown in 40 Figure 1, or to a horizontal support 7, as shown in Figure 5, the square form of the placard permitting it to be displayed upright with the holder in either position.

Two opposing and one of the intermediate 45 edges of the sheet are turned over to form flanges 8 and 9, respectively. These flanges are slightly separated at the corners of the holder to form drip openings 10 one of which is situated at the lowest point of the holder 50 when in the position shown in Figure 1, and

the other when it is in the position shown in Figure 5. Any rain entering the holder is thus allowed to drain off. Secured to each of the flanges 8 by rivets 11 is a spring arm 12, 55 holes 13 (Figure 2) being formed in the plate for the passage of a tool to support the rivet during the process of riveting. Carried by the arms 12 is an angle-iron bar one flange 14 of which overlies the placard within the holder, while the other flange 15, in its normal position, closes the side of the holder 60 through which the placards are inserted and withdrawn. A finger piece 16 is riveted to the flange 14 by means of which the angle-iron can be moved against the tension of the 65 spring arms to uncover the open side of the holder to insert or withdraw placards. The turned over ends of the arms 12 project slightly beyond the edge of the flange 15 (as best shown at Figure 4) to form guards 17 to 70 bear against the edges of the placard and thus prevent accidental contact of the flange with the printed parts of the placards as they are moved into and out of the holder and the marring of their faces. In order to prevent 75 bending of the spring arms beyond the limit of resiliency the flange 14 is extended to form arms 18 having their ends bent to form stops 19.

Our holder, while especially adapted for 80 use with permanent metallic placards, may also be used to hold paper placards, and owing to the fact that the open side of the holder is completely and effectively closed by the angle-iron and cannot be accidentally left 85 open, there is no danger of the paper placard blowing out of the holder as might otherwise occur due to the air currents generated by the rapid movement of the car.

Having fully described our invention, 90 what we claim as new and desire to secure by Letters Patent of the United States is:

1. In a device of the class described, the combination with a rectangular body portion provided at three sides with ways to receive 95 the edge of a placard, the fourth side being adapted to allow the insertion and removal of the placard, of a spring actuated closure member movable across the plane of the holder in a direction perpendicular thereto, 100

said member extending across and completely covering the said fourth side when in normal position.

2. In a device of the class described, the combination with a rectangular body portion provided at three sides with ways to receive the edge of a placard, the fourth side being adapted to allow the insertion and removal of the placard, of a spring actuated angle bar extending across and completely covering the said fourth side when in normal position, said angle bar being movable across the plane of the holder in a direction perpendicular thereto.

3. In a device of the class described, the combination with a rectangular body portion having three of its edges turned over to form integral flanges providing ways to receive the edges of a placard, the fourth side being adapted to allow the insertion and removal of the placard, of a pair of spring arms secured to flanges at opposite sides of the body, and an angle bar carried by said arms for closing said fourth side.

4. In a device of the class described, the combination with a rectangular body portion provided at three sides with ways to receive the edges of a placard, the fourth side being adapted to allow the insertion and removal of the placard, of a pair of spring arms carried at opposite sides of the body, an angle bar secured to said arms for closing the fourth side, and a stop for limiting the movement of said bar.

5. In a device of the class described, the combination with a rectangular body portion provided at three sides with ways to receive the edges of a placard, the fourth side being adapted to allow the insertion and removal of the placard, a spring actuated closure member for said fourth side, and a pair of guards at the ends of said member for preventing accidental contact of the member with the placard when the latter is inserted or withdrawn.

45. In testimony whereof, we hereunto affix our signatures this 16th day of July, 1928.

WARREN E. COOPER.
FREDERICK K. HABENICHT.
